(57) **CLAIM**

The ornamental design for a mobility device, substantially as shown and described.

DESCRIPTION

FIG. 1 is a top, perspective view of the mobility device; the view showing my new design;

FIG. 2 is a front elevation view thereof;

FIG. 3 is a side elevation view thereof;

FIG. 4 is a side elevation view thereof;

FIG. 5 is a top view thereof;

FIG. 6 is a bottom view thereof;

FIG. 7 is a rear elevation view thereof;

FIG. 8 is a bottom, perspective thereof; and,

FIG. 9 is a top, perspective view thereof; the view showing the mobility device in a folded position.

A mobility device. The broken lines showing portions of the design in the figures are included for the purpose of illustrating environment and unclaimed features and forms not part of the claimed design.
